UNITED STATES PATENT OFFICE.

CHARLES H. JOCKMUS, OF ANSONIA, CONNECTICUT.

SPLASH-FEED OIL-CUP.

1,313,385.

Specification of Letters Patent. Patented Aug. 19, 1919.

Application filed March 1, 1919. Serial No. 279,958.

To all whom it may concern:

Be it known that I, CHARLES H. JOCKMUS, a citizen of the United States, residing at Ansonia, county of New Haven, State of Connecticut, have invented an Improvement 5 in Splash-Feed Oil-Cups, of which the following is a specification.

This invention relates to oil cups of the splash feed type and has for its object to 10 provide a construction that will avoid the irregularity and uncertainty of feeding that has heretofore existed in all splash feed oil cups, so far as I am aware, and insure regularity and certainty of feeding so long as an 15 appreciable amount of oil remains in the reservoir.

With this and other objects in view I have devised the novel improvement in splash feed oil cups which I will now describe referring 20 to the accompanying drawing forming a part of this specification and using reference characters to indicate the several parts.

Figure 1 is an elevation of my novel oil 25 cup;

Fig. 2 a longitudinal section thereof, partly in elevation;

Fig. 3 a perspective view of the stem detached, and

Fig. 4 is a longitudinal section partly in elevation illustrating a variant form of the 30 invention.

10 denotes the body, which is provided with an oil reservoir 11, and with an externally 35 threaded hub 12 by which it is attached in place for use. 13 denotes the stem, the lower end of which has threaded engagement with the hub, and which is provided with a head 14 at its upper end, and a 40 longitudinal bore 15 which is in alignment with a similar bore 16 in the hub. 17 denotes a cap which is adapted to slide closely over the body and is provided with a central hole 18 through which the stem passes 45 freely but which is of less diameter than the head. A spring 19 bearing against the inner side of the cup and the bottom of the reservoir acts to press the cap tightly 50 against the head and thus keep the reservoir closed. In order to fill the reservoir it is simply necessary to press the cap downward against the power of the spring which leaves the reservoir uncovered and permits 55 convenient filling.

This type of oil cups is adapted for use

upon moving parts, as upon engine crank rods, the movement of the part carrying the cup causing the oil in the reservoir to splash up on the stem. A plurality of holes 20 leading from the exterior of the stem to 60 the bore thereof receives some of the oil that is splashed up on the stem and conducts it into the bore, the oil passing down the bores in the stem and the hub to the place where it is required. In order to facilitate 65 the passage of oil from the exterior of the stem into the bore, holes 20 are caused to incline downward from the exterior of the stem to the bore. This, however, does not at all times insure a regular and constant 70 supply of oil through the bore. I, therefore, provide the exterior of the stem with a circular trough 21 from which the holes lead downward at an angle into the bore. This trough catches and retains oil that is 75 splashed up on the stem thereby insuring a constant and uniform supply of oil through the holes in the stem to the bore and thence to the part or parts to be lubricated.

The special manner in which the trough 80 is formed is not an essential feature of the invention. In Figs. 2 and 3 I have shown a form in which the trough is formed by removing metal entirely around the stem, the trough being in fact a circular groove in the 85 stem, both walls of which are downwardly extending inclines which meet at the bottom of the groove.

In the form illustrated in Fig. 4, the stem is provided with a collar around the outside thereof in which the trough is formed. 90

Having thus described my invention, I claim:

An oil cup comprising a body having a reservoir and an attaching hub, a stem secured in the hub and having a head, the stem and hub being provided with a bore and the stem being provided intermediate the hub and the head with a circular trough and with inclined openings leading from the 100 trough into the bore, a cap adapted to slide closely over the body and having a hole through which the stem passes freely but which is of less diameter than the head, and a spring acting to normally hold the cap 105 against the head and retain the reservoir closed.

In testimony whereof I affix my signature.

CHARLES H. JOCKMUS.
